UNITED STATES PATENT OFFICE.

CHARLES L. MILLER AND EMMA L. N. MILLER, OF YONKERS, NEW YORK.

PARCEL-POST EGG-PACKAGE.

1,121,110.

Specification of Letters Patent. Patented Dec. 15, 1914.

Application filed January 16, 1914. Serial No. 812,382.

To all whom it may concern:

Be it known that we, CHARLES L. MILLER and EMMA L. N. MILLER, citizens of the United States, and residing at Yonkers, in the county of Westchester and State of New York, have invented certain new and useful Improvements in Parcel-Post Egg-Packages, of which the following is a specification, such as will enable those skilled in the art to which it appertains to make and use the same.

This invention relates to means for shipping eggs by parcels post, and the object thereof is to provide a package for this purpose, by means of which, or in which, the eggs may be sent to any place, at any distance, without danger of breakage; a further object being to provide a package of the class specified which may be used for the purpose of mailing other breakable articles, without danger of breaking the same or injury thereto.

The invention is fully disclosed in the following specification, of which the accompanying drawings form a part, in which the separate parts of our improvement are designated by suitable reference characters in each of the views, and in which;

Figure 1 is a plan view of our improved package device, and showing the same partly open and with one part broken away;—Fig. 2 a cross section on the line 2—2 of Fig. 1, but showing the package entirely closed;—Fig. 3 a view similar to Fig. 2, but showing another method of closing the package;—Fig. 4 a plan view of a division and packing strip which we employ;—Fig. 4^a a diagrammatic view showing the method of folding the division and packing strip, shown in Fig. 4;—Fig. 5 a view similar to Fig. 1, but showing the package entirely open, and showing a modification with a part of the construction broken away;—Fig. 6 a perspective view and showing a modified form of a division and package strip;—Fig. 7 a perspective view showing a means for packing each individual egg separately in our improved package, and;—Fig. 8 a cross section on the line 8—8 of Fig. 5.

In the practice of our invention, as shown in Figs. 1 to 4, we provide a package box or receptacle *a* composed of paste board, card board, or other sheet, fibrous material having an amount of flexibility sufficient to en-

able it to be easily folded, and the said box or receptacle *a* comprises a bottom *a*², ends *a*³ and sides *a*⁴, provided at their top edges with overlapping flaps *a*⁵ adapted to be folded over so as to close the top of the box or receptacle in two different ways, as shown in Figs. 2 and 3.

The box or receptacle *a* may be of any desired length, but its transverse dimensions are preferably such as to contain two rows of eggs *b*, and in practice, the bottom *a*², ends *a*³ and sides *a*⁴, together with the flaps *a*⁵ of said sides *a*⁴, are provided with a comparatively thick packing *c* of cotton batting, felt or other suitable fibrous material having absorptive qualities, and which will also act as a cushion, and this material, in practice, is preferably secured to a fabric body *c*² which, in turn is secured to the inner walls of the box or receptacle by a suitable paste, or in any other way.

In the construction shown in Figs. 1 to 4 inclusive, the box or receptacle is intended to hold one dozen eggs arranged in two parallel rows, and in practice, we provide two division strips *d* composed of flexible card board, paste board, or similar material, and adapted to be folded at *d*² to form upwardly directed loops *d*³, and the parts *d*⁴ between the loop folds *d*³ are provided with side edge wing members *d*⁵, and the division and packing strips *d* and wing members *d*⁵ are provided on their inner sides with a thick layer of fibrous, cushioning and absorbent material *d*⁶ similar to the cushioning, packing and absorbent material *c*.

In filling the package box or receptacle with eggs, two division and packing strips *d* are placed therein and folded to form the transverse vertical loop members *d*³ between each transverse pair of which, an egg *b* is placed, and the wing members *d*⁵ are folded over said eggs, as clearly shown in Figs. 1, 2 and 3, and the end portions *d*⁷ of the division and packing strips are also folded upwardly, as shown at *d*⁸, and this forms a complete individual nest for each egg, and the side flaps *a*⁵ may then be folded over the tops of the separate rows of eggs and downwardly between the same, as shown at *a*⁶, in Fig. 2, or said flaps may be overlapped, as shown at *a*⁷ in Fig. 3, after which the package is secured by passing a cord, strap or similar device, a number of times around the same, transversely thereof, and said

cord, strap or similar device may be passed around the package longitudinally thereof so as to securely hold and close said package.

The packing *c* does not extend quite to the edges of the flaps *a*⁵ as shown in Figs. 1, 2 and 3 and this facilitates the insertion of said flaps, or the edges thereof, between the separate rows of eggs as shown in Fig. 2.

Our invention is not limited to any particular method of constructing the box or receptacle forming the body portion of the package, and the ends *a*³ may be formed integrally with the bottom *a*², and the sides *a*⁴, or said ends may be formed separately from the sides, and modifications of and changes in these and other features of construction herein shown and described may be made, without departing from the spirit of our invention or sacrificing its advantages; and in Figs. 5 to 8 inclusive, we have shown certain modifications of the construction shown in Figs. 1 to 4 inclusive.

In Figs. 5 and 8, we have shown a modification of the box or receptacle, in which separate nests *e* for the eggs are formed, by means of a central longitudinal strip *e*² of cotton, cotton batting, felt or similar fibrous material, whereby the box or receptacle is divided into two longitudinal chambers, which chambers are sub-divided by transverse packing blocks *e*³ composed of fibrous cushioning and absorbing material to form the nests *e*, in which the eggs are placed, after which the box or receptacle is closed and secured, as hereinbefore described, with reference to the construction shown in Figs. 1 to 4 inclusive, and this construction, as will be seen, also provides a separate nest or receiver for each egg, and the amount of packing, cushioning and absorbing material which surrounds and encloses the separate eggs at all points is sufficient to secure their transportation without danger of breaking the same, under usual conditions, but, if at any time, one or more eggs should be broken, the liquid contents thereof would be absorbed by the cushioning and absorbing material, and would not spread to the compartments in which the other eggs are placed.

In Fig. 6, we have shown a modified form of the division and packing strip shown in Fig. 4, which consists of a strip *d*⁰ of card board, paste board or other fibrous material, folded into loops and provided on its inner side with a packing *d*¹⁰ similar to the packings *d*⁶ and *c*, shown in Figs. 1 to 3 inclusive, but the division and packing strips *d*⁰ are intended for the same purpose as the division and packing strip or strips *d*, but the side wing members are omitted, and in the use of folding, packing and division strips made, as shown in Fig. 6, longitudinal and

division strips *e*^a, as shown in Fig. 5, would be employed.

We have also shown in Fig. 7, a method of packing and securing each individual egg separately, in which we employ an individual receptacle *f* composed of card board, pasteboard, or similar material, and having side wings *f*² which are lined, in practice, with absorbing and cushioning material, as shown in Figs. 1 to 3 inclusive, and a number of these devices, with eggs therein, may be placed in the box or receptacle in a longitudinal row, or in parallel rows, after which the flaps *a*⁵ may be folded, as shown in Fig. 3. If only one row of eggs are packed, or as shown in Fig. 2, if two rows of eggs are packed, or either form of folding the side flaps *a*⁵ may be employed, as circumstances may render possible.

If our improved receptacle should be found, in practice, to be not sufficiently strong to resist compression and consequent breakage of the eggs, said receptacle or package may be inclosed in an outer casing or crate of wood or other suitable material, and in this way a package may be formed which would resist any actual force to which the package might be subjected in its shipment by mail, and while we have shown and described our improved package as designed particular for shipping or mailing eggs, it will be understood that said package may be employed for shipping or mailing other small articles of various kinds and classes.

Having fully described our invention, what we claim as new and desire to secure by Letters Patent is:

A parcel post mailing package, comprising an oblong receptacle composed of flexible fibrous material and closed at the ends and open at the top and the sides of which are provided with overlapping top flaps to close the open top of said receptacle, all the parts of said receptacle including the flaps, except at the edges thereof, being lined at all points with cushioning and absorbing fibrous material and said receptacle being also provided with means for forming separate nests or receptacles for the articles to be mailed and consisting of removable parts composed of flexible fibrous material provided on its inner side with thick cushioning and absorbing material adapted to closely fit around the articles to be mailed.

In testimony that we claim the foregoing as our invention we have signed our names in presence of the subscribing witnesses this 13th day of January 1914.

CHARLES L. MILLER.
